(57) **CLAIM**

The ornamental design for a sport bottle, as shown and described.

DESCRIPTION

FIG. 1 is a top front perspective view of our new design for a sport bottle;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

(Continued)

FIG. 7 is a top view thereof; and,
 FIG. 8 is a bottom view thereof.
 The portion of the sport bottle shown in broken lines form
 no part of the claimed design.

1 Claim, 7 Drawing Sheets
